[57] CLAIM

The ornamental design for a seating unit for an aircraft
cabin, as shown and described.

DESCRIPTION

FIG. 1 is a top plan view of a seating unit for an aircraft
cabin, showing our new design;

FIG. 2 is a side elevational view thereof, taken from the
bottom of FIG. 1;

FIGS. 3 and 4 are views similar to FIGS. 1 and 2, respec-
tively, but showing the parts in a first alternative position
thereof;

FIG. 5 is a view similar to FIG. 1 but showing the parts in
a second alternative position;

FIGS. 6 and 7 are views similar to FIG. 2 but showing the
parts in respectively third and fourth alternative positions;
and,

FIGS. 8 and 9 are top, side and rear perspective views
thereof in further alternative positions.

The portions of the seating unit which have not been shown
form no part of the claimed design.
